UNITED STATES PATENT OFFICE.

ARTHUR J. EMERY, OF SELINSGROVE, PENNSYLVANIA.

BOTTLE CAP.

Application filed January 21, 1927. Serial No. 162,551.

This invention relates to container caps and its primary object is to provide a sealing cap including means whereby the cap can be easily and expeditiously removed 5 from its container with very little effort on the part of the operator.

A further object of the invention is to provide a bottle cap including an opening attachment therefor adapted for removing the 10 cap from the bottle without the use of tools or the like.

Another object of the invention is to provide a bottle cap including an opening attachment therefor, that is extremely simple 15 in construction, contains few parts and is inexpensive to manufacture.

This invention also consists in certain other features of construction and in the combination and arrangement of the several 20 parts, to be hereinafter fully described, illustrated in the accompanying drawings and specifically pointed out in the appended claims.

In describing my invention in detail, reference will be had to the accompanying 25 drawings wherein like characters denote like or corresponding parts throughout the several views, and in which:

Figure 1 is a vertical sectional view taken 30 through the neck of the bottle and showing my novel cap secured thereto with the opening attachment arranged in normal position.

Figure 2 is a similar view showing the 35 opening attachment disposed to operative position and the manner in which it removes the cap.

Figure 3 is a top plan view of my cap and attachment per se.

Referring to the drawings in detail the 40 letter A indicates the neck of a bottle which is provided with the usual grooved head B for receiving a cap, and in the present instance the cap includes the usual crimped flange 1 adapted to be received in said groove 45 as best shown in Figure 1. The top 2 of the cap is provided with a centrally disposed opening 3 adapted to receive my novel opening attachment which is provided with a body of substantially right angle configuration 50 with a hook 4 formed on the arm 5 thereof while the arm 6 terminates in a thumb piece 7 with a projection 8 extending therefrom at its juncture with the thumb piece 7. The projection 8 provides a shoulder for engagement with the flange 1 as 55 shown in Figure 1 of the drawings, for re-

taining the attachment in its normal position. The hook 4 is provided with a rounded bight portion 9 and is arranged in the opening 3 for engagement with a disk plate 60 10 having a concavity 11 therein to accommodate the hook in the manner as shown in Figure 1, but when the thumb piece 7 is actuated and the attachment is moved to the position as shown in Figure 2, it will be 65 obvious that such movement will cause the end of the hook to engage the cap 2 and remove the same from the bottle and by providing the rounded bight portion to the hook, the same is provided with a cam surface 70 whereby the attachment can be easily operated as will be obvious. In order to provide a seal between the cap and the bottle, I have shown the customary sealing gasket 12 which is disposed between the top of the 75 head B and the disk plate 10 when the cap is attached to the bottle.

It is thought from the foregoing description that the advantages and novel features of my invention will be readily apparent. 80

I desire it to be understood that I may make changes in the construction and in the combination and arrangement of the several parts, provided that such changes fall within the scope of the appended claims. 85

What I claim is:

1. A bottle cap of the character described comprising a top provided with a centrally disposed opening, means formed with said top for securing the same to a bottle, a disk plate included in said cap and being provided with a centrally disposed concavity, a sealing gasket arranged upon the bottom of said disk plate, means for removing said cap from the bottle and being provided with a hooked end received in said opening and disposed in said concavity for engagement with the top of said disk plate, a thumb piece for said removing means, means on said thumb piece for retaining the removing means in normal position, and said thumb piece being operable for causing the terminal of said hooked end to engage the top and remove the cap from the bottle. 95

2. In a bottle cap, a top having a centrally disposed opening, means for securing said top to a bottle, a metallic disk plate provided with a centrally disposed concavity and arranged below said top, a sealing gasket for said disk plate, means for removing said cap from the bottle and including a body having right angled disposed arms, a 100 110

hooked end formed on one of said arms and being provided with a rounded bight portion, a thumb piece formed on the end of the other of said arms, a projection formed on the thumb piece and adapted to be secured to a cap for securing said removing means in normal position, and said hooked end being operable by the thumb piece for movable

engagement with the top and disk plate respectively, in a manner whereby the bight portion acts as a fulcrum and the terminal of said hooked end engages with the top for removing the cap from the bottle. ¹⁰

In testimony whereof I affix my signature.

ARTHUR J. EMERY.
